COUNTING DEVICES FOR USE WITH KNITTING NEEDLES

Norman Thomas Sanders, Mapleborough Green, Studley, England, assignor to Needle Industries Limited, Birmingham, England, a British company

Application January 21, 1958, Serial No. 710,330

7 Claims. (Cl. 116—133)

This invention relates to a counting device for use in association with a knitting needle, which counting device comprises relatively rotatable inner and outer sleeves, the former having circumferentially spaced numerals marked thereon and the latter having a viewing aperture or window through which one of the numerals or a group thereof can be exposed to view.

In use such counting devices are threaded on to the shank of a knitting needle and are arranged to be located against axial displacement with respect to said needle, the knitter using the device for the purpose of counting rows or stitches as the knitting proceeds.

One object of the present invention is to provide a new or improved construction of such a counting device which is relatively light in weight and comparatively economical to produce.

A further object of the present invention is to provide a counting device wherein relative rotation of the two sleeves avoids any rubbing action on the numerals which might otherwise cause erasure of such numerals.

Yet a further object of the present invention is to provide a counting device which can be quickly and easily adjusted as counting proceeds and in which the set or predetermined positions of adjustment are maintained against inadvertent disturbance thereof.

In accordance with the present invention I provide in a counting device for use in association with a knitting needle comprising an inner sleeve having an axially extending bore, numerals circumferentially spaced around the outer surface of said inner sleeve and retaining means associated with said bore for locating said device axially on a knitting needle inserted into the bore; the provision in combination of an elastically deformable outer sleeve rotatably mounted on said inner sleeve and having a viewing aperture adapted to expose said numerals and means on the inner sleeve cooperating with the outer sleeve to deform said outer sleeve to a diameter which is different from its natural unrestrained diameter, the relative dispositions of at least a part of one of the two circumferential surfaces of the deformable outer sleeve and an adjacent part of the inner sleeve being such as to provide frictional engagement between them so that the two sleeves are yieldably retained against inadvertent relative rotation.

The invention will appear more clearly from the following detailed description when taken in connection with the accompanying drawings, showing by way of example a preferred embodiment of the inventive idea.

The invention is illustrated in the accompanying drawings wherein:

Figure 1 is a perspective view of one construction of counting device in accordance with the present invention.

Figure 2 is a perspective view of the outer sleeve of such device.

Figure 3 is a diametral cross section of such device, and

Figure 4 is a cross sectional view on the line 4—4 of Figure 3.

2

The counting device comprises an outer sleeve 10 made of resilient strip metal, for example, stainless steel, brass, or aluminium alloy, preferably having a thickness of about 0.010", bent into the form of a regular polygon having ten sides.

Typically such outer sleeve 10 is about $\frac{3}{8}$ " in length and its internal dimensions, measured between opposed sides of the polygon in the free unstressed state prior to assembly in the counting device may also be about $\frac{3}{8}$ ".

10 The edges 11 of the strip at its free ends are spaced apart circumferentially from each other to provide an axially extending gap 12, which, as illustrated, occupies part of one side of the polygon, although it could constitute the whole of such side. The illustrated form is preferred in that it avoids any outward projection of the edges 11 of the metal whereas were these edges to be situated in co-incidence with the junction of the gapped side with the next succeeding side of the polygon, said edges 11 would project outwardly to some extent and in such a case it would be desirable to round or smooth such edges so as to prevent undesirable sharpness.

15 The device further comprises an inner sleeve 13 which comprises two main parts 14 and 15 which are assembled co-axially with each other and with the outer sleeve 10 and are rotatable relatively to each other and to the outer sleeve 10.

20 Each of the two parts 14 and 15 of the inner sleeve comprises an inner drum element as seen respectively at 16 and 17 (see Figure 3) of a diameter such as to fit 30 within the outer sleeve 10 and still leave an annular clearance space 18 between the outer sleeve 10 and the outer face of each drum element 16 and 17. Each part 14 and 15 of the inner sleeve further comprises an end cap portion seen respectively at 19 and 20.

25 In the case of the inner sleeve part 14 the end cap portion comprises firstly an extension 21 being of slightly greater diameter than the drum element 16 and secondly an outer ring 22 spaced radially from this extension 21 and connected to it integrally at its outer end so as to define an annular channel 23 which is directed axially inwardly to receive an adjacent end portion of the outer sleeve 10.

30 The drum element 17 also includes an integral extension 24 of larger diameter than said drum element 17 but instead of said extension 24 being united integrally with an outer ring 25 defining an annular channel 26, it is secured as, for example, by adhesive, in a channel formed between the ring 25 and an inner tubular portion 27 integral with said ring 25 and engaging within the drum element 17.

35 The drum element 17 is itself integrally connected with a further tubular portion 28 at once end thereof, which tubular portion 28 engages within the drum element 16 and is formed after assembly with a retaining flange 29 at its outer end in the manner described and claimed in my copending U. S. patent application, thereby retaining the two parts 14 and 15 of the inner sleeve against axial separation. Said two parts 14 and 15 are constrained against inward axial displacement by engagement of the inner end face of the drum element 16 with a laterally extending shoulder 30 formed at the junction between the portion 28 and the drum element 17, this limiting separation being such as to provide axial clearance spaces 31 and 32 between the ends of the outer sleeve 10 and the bases of the annular channels 23 and 26.

40 It will be understood that the parts of the inner sleeve above described may be made of any suitable material. For example, they may be formed as mouldings from a suitable synthetic resin material, preferably of the thermoplastic kind to facilitate formation of the flange 29.

45 The rings 22 and 25 which form the outer sides of the

channels 23 and 26 respectively are so shaped in cross section in a plane perpendicular to the axis of the inner sleeve that at least their inner faces are of substantially regular polygonal form, the number of sides corresponding to the number of sides incorporated in the outer sleeve 10. Conveniently the rings 22 and 25 are of uniform wall thickness (see Figure 4) so that they are also of polygonal form externally and thus assist in grasping and rotating one of the rings whilst holding the other against rotation.

The cross sectional dimensions afforded internally by the rings 22 and 25 are somewhat less than the corresponding external dimensions of the outer sleeve 10 when in its free unstressed state so that said outer sleeve 10 has to be contracted circumferentially and radially to some extent before its end portions 33 and 34 can be assembled in the channels 23 and 26 respectively so that said outer sleeve 10 is then retained by virtue of its own resilience in pressure contact with the inner faces of the rings 22 and 25.

By virtue of the polygonal cross section of the sleeve and the rings, ten stopping positions are defined, but either part 14 or 15 of the inner sleeve can be rotated against the resistance imposed at these stopping positions. Such rotation effects a further temporary contraction of the outer sleeve, which is allowed to expand again when the next stopping position is reached.

This temporary further contraction is effective only at one end of the outer sleeve 10 because the innate resilience of the outer sleeve maintains its other end portion in effective engagement with the polygonal internal face of the ring embracing it at this end. Thus, relative rotation between the outer sleeve 10 and one of the end caps will tend to take place at one end of the outer sleeve only, being that end at which such rotation is initiated, some additional constraint being imposed against relative rotation between the outer sleeve and the end cap portion at the other end of the outer sleeve.

In practice it will almost always be the case that the yieldable restraint established between the outer sleeve 10 and one of the end cap portions 19 and 20 of the inner sleeve is somewhat greater than that established between the outer sleeve 10 and the other of said end cap portions. Thus, to ensure that the outer sleeve remains stationary with respect to the desired end cap portion, the outer sleeve 10 is provided with at least one torque anchor projection on its outer face, such projection or projections being positioned to come into contact with the tips of the user's finger and thumb or fingers when grasping that end cap portion which is to be held stationary. Preferably two such torque anchor projections are provided, these being in the form of axially extending ribs 35 and 36, each having a height measured in a radial direction such that it is not more than slightly below or not more than slightly proud of the outer circumferential faces of the rings 22 and 25 of the end cap portions. This allows the requisite restraint to be imposed upon rotation of the outer sleeve 10 with respect to one of the end cap portions without obstructing desired rotation of the other end cap portion. Conveniently the ribs 35 and 36 are spaced from the gapped side of the polygon formed by the outer sleeve by one intervening side, as may be seen in Figure 2.

To further assist the desired mode of use, i. e. rotation of one end cap portion whilst the outer sleeve and the other end cap portion are held stationary, the axial spacing between the innermost ends of the rings 22 and 25 should preferably not exceed about $\frac{1}{2}$ " or be less than about $\frac{3}{16}$ ", the preferred value being about $\frac{5}{16}$ ". This last dimension is, to some extent, related to the height or extent of radial projection of the outer faces of the rings 22 and 25 with respect to the outer face of the outer sleeve 10. The ratio of such radial projection to the axial spacing above referred to is, in a typical case, about $\frac{1}{4}$ to $\frac{1}{5}$ but it will be understood that there may

be some departure from this preferred range according to the size in which the counting device as a whole is made.

The drum elements 16 and 17 are each marked with numerals 0-9 at equally circumferentially spaced positions and the gap 12 is of sufficient width to enable one such numeral from each drum element to be exposed at a time, it being understood that the numerals will be marked in such positions as to be completely exposed when the parts 14 and 15 of the inner sleeve occupy 10 the stopping positions with respect to the outer sleeve previously referred to.

The tendency for the outer sleeve to be maintained in pressure contact with the rings 22 and 25 maintains the existence of the clearance space 18 and consequently 15 there is no rubbing contact between the outer sleeve 10 and the faces of the drum elements 16 and 17 upon which the numerals are marked so that any tendency to erasure of the numerals is avoided.

Some inward contraction of the outer sleeve occurs 20 in moving one of the end caps from one stopping position to another and some inward contraction may also occur in consequence of pressure exerted against the ribs 35 and 36. However, the extension portions 21 and 24 25 of the drum elements 16 and 17 serve by their larger diameters positively to prevent the outer sleeve coming into contact with the outer faces of the drum elements 16 and 17 so as further to eliminate the risk of numeral erasure.

The counting device is intended to be threaded on to 30 a knitting needle which is passed through the bore afforded by the portions 27 and 28.

The device is retained against axial displacement by spaced parallel coil springs 37 and 38, the end portions of which are retained between the end of the portion 27 35 and the internal junction between the drum element 17 and the portion 28 formed integrally therewith. Such retaining means are the subject of my co-pending U. S. patent application, to which reference may be had for a fuller description.

The construction above described is extremely compact and light, the overall length measuring, for example, about $\frac{3}{4}$ ", with the outside diameter of the end cap portions being, for example, about $\frac{1}{2}$ ", whilst the total weight may be 2 grams or less. The counting device can thus 40 be threaded on to the end of a knitting needle which is in use without any significant increase in the overall weight of that portion of the knitting needle in the region of the knob.

It will be appreciated that various modifications may 50 be made to the construction as above described without departing from the spirit of the invention.

What I claim then is:

1. In a counting device for use in association with a knitting needle comprising an inner sleeve having an axially extending bore, numerals circumferentially spaced around the outer surface of said inner sleeve and retaining means associated with said bore for locating said device axially on a knitting needle inserted into the bore; the provision in combination of an elastically deformable outer sleeve rotatably mounted on said inner sleeve and having a viewing aperture adapted to expose said numerals and means on the inner sleeve co-operating with the outer sleeve to deform said outer sleeve to a diameter which is different from its natural unrestrained diameter, the 55 relative dispositions of at least a part of one of the two circumferential surfaces of the deformable outer sleeve and an adjacent part of the inner sleeve being such as to provide frictional engagement between them so that the two sleeves are yieldably retained against inadvertent 60 relative rotation.

2. In a counting device for use in association with a knitting needle comprising an inner sleeve having an axially extending bore, numerals circumferentially spaced around the outer surface of said inner sleeve and retaining 65 means associated with said bore for locating said

device axially on a knitting needle inserted into the bore; the provision in combination of an outwardly expandable outer sleeve rotatably mounted on said inner sleeve and having a viewing aperture adapted to expose said numerals and an end cap portion connected to said inner sleeve and frictionally engaging with said outwardly expandable outer sleeve to confine it to a diameter which is less than its natural unrestrained diameter, the surface of said outer sleeve adjacent said numerals provided on the inner sleeve being spaced away from said inner sleeve.

3. In a counting device for use in association with a knitting needle comprising an inner sleeve having an axially extending bore, numerals circumferentially spaced around the outer surface of said inner sleeve and retaining means associated with said bore for locating said device axially on a knitting needle inserted into the bore; the provision in combination of an outwardly expandable outer sleeve, a radially outwardly directed face provided on said outer sleeve, an end cap portion connected to said inner sleeve and a radially inwardly directed face provided on said end cap portion, at least one of said radially outwardly and radially inwardly directed faces being provided with a plurality of non-positive stopping formations, said radially inwardly and radially outwardly directed faces engaging each other in one of a plurality of stopping positions in which the inner and outer sleeves are yieldably retained against inadvertent relative rotation and in which at least one of said numerals is in register with said viewing aperture.

4. In a counting device for use in association with a knitting needle comprising an inner sleeve having an axially extending bore, numerals circumferentially spaced around the outer surface of said inner sleeve and retaining means associated with said bore for locating said device axially on a knitting needle inserted into the bore; the provision in combination of an outer sleeve rotatably mounted on said inner sleeve and having a viewing aperture adapted to expose said numerals, an outwardly expandable resilient portion provided on said outer sleeve and of substantially regular polygonal shape in cross section perpendicular to the axis of said outer sleeve, and an end cap portion connected to said inner sleeve embodying an inwardly facing axially directed channel wherein the outer side faces of such channel are of substantially regular polygonal form in cross section corresponding with that of said outer sleeve, said outwardly expandable resilient portion of the outer sleeve being adapted to enter into said channel and engage with said outer side faces thereof so as to provide a plurality of non-positive stopping positions.

5. In a counting device for use in association with a knitting needle comprising an inner sleeve having an axially extending bore, numerals circumferentially spaced around the outer surface of said inner sleeve and retain-

ing means associated with said bore for locating said device axially on a knitting needle inserted into the bore; the provision in combination of an outwardly expandable outer sleeve rotatably mounted on said inner sleeve and having a viewing aperture adapted to expose said numerals, a pair of axially spaced end cap portions connected to said inner sleeve, said outwardly expandable outer sleeve frictionally engaging with each of said end cap portions so as yieldably to retain the inner and outer sleeves against inadvertent relative rotation from a set position, the inner surface of the outer sleeve being spaced from the adjacent surface of that portion of the inner sleeve provided with said numerals.

10 6. A counting device for use in association with a knitting needle comprising an inner sleeve having an axially extending bore, numerals circumferentially spaced around the outer surface of said inner sleeve, an outwardly expandable resilient outer sleeve rotatably mounted on said inner sleeve and having a viewing aperture adapted to expose said numerals, a torque anchor projection provided on and extending radially outwardly from said outer sleeve, said outer sleeve being of substantially regular polygonal shape in cross section perpendicular to its axis, an end cap portion connected to said inner sleeve and embodying an inwardly facing axially directed channel, and a plurality of stop-producing formations such as flat faces provided in said channel, said outwardly expandable resilient outer sleeve being adapted to enter into said channel and engage with said stop-producing formations so as to establish a plurality of non-positive stopping positions.

15 7. A counting device for use in association with a knitting needle comprising an inner sleeve having an axially extending bore, numerals circumferentially spaced around the outer surface of said inner sleeve, an outwardly expandable resilient outer sleeve rotatably mounted on said inner sleeve, said outer sleeve being of substantially regular polygonal shape in cross section perpendicular to its axis and having a viewing aperture adapted to expose said numerals and an end cap portion connected to said inner sleeve and embodying an inwardly facing axially directed channel wherein the outer side faces of such channel are of substantially regular polygonal form in cross section corresponding with that of said outer sleeve, said outwardly expandable resilient outer sleeve being adapted to enter into said channel and engage with said outer side faces thereof so as to provide a plurality of non-positive stopping positions.
